UNITED STATES PATENT OFFICE.

SETH A. CRONE, OF EAST ORANGE, NEW JERSEY, ASSIGNOR TO BUFFALO BRAKE BEAM COMPANY, OF NEW YORK, N. Y., A CORPORATION OF NEW YORK.

SAFETY HANGER FOR BRAKE RODS.

Application filed July 9, 1924. Serial No. 724,943.

To all whom it may concern:

Be it known that I, SETH A. CRONE, a citizen of the United States, and resident of East Orange, in the county of Essex and State of New Jersey, have invented certain new and useful Improvements in Safety Hangers for Brake Rods, of which the following is a specification.

The invention resides in a novel safety hanger adapted for use in supporting the bottom connection rod of car brake mechanism in the event that either of the pins positioning said rod become displaced.

Various forms of safety hangers for the connection rod of brake mechanisms are well known, and these have usually been in the form of hanging stirrups or loops riveted or bolted to the spring plank or other part of the truck and usually located at one side only of the spring plank.

In accordance with my invention I provide a safety hanger in the form of an integral rod which extends diagonally below the spring plank from one transverse side of said plank to the other transverse side thereof and is formed below the spring plank, with a depending open-top yoke or saddle through which the connection rod freely passes and which is approximately below the middle portion of said rod and hence in an advantageous position with reference to the purposes of the hanger. A further feature of my invention is that the ends of the safety hanger rod are formed with loops or eyes to receive or be engaged with the carrier bars of four-point suspensions, whereby said hanger may be properly supported without the use of rivets or bolts. By reason of the diagonal disposition of the safety hanger, with its ends on diagonally opposite carrier bars and close to diagonally opposite portions of the sides of the spring plank, said hanger becomes very rigidly held in position and may, if necessary, be tightened on the parts its ends engage by being bent or forced downwardly at its middle portion.

Some car trucks do not possess carrier suspension bars for the brake beams but do have safety angle bars of known character to prevent the brake-beams from falling to the track in case of their being released from the brake hangers, and in car trucks of this character my safety hanger at its looped ends will be supported by said angle bars in

the same manner that it is supported on the carrier suspension bars when said bars are present.

The invention will be fully understood from the detailed description hereinafter presented, reference being had to the accompanying drawings, in which:

Fig. 1 is a top view, partly broken away, of a car-truck having inside hung trussed brake-beams and equipped with the safety hanger of my invention for the bottom connection rod of said beams;

Fig. 2 is a vertical transverse section through a portion of the same, taken on the dotted line 2—2 of Fig. 1;

Fig. 3 is a top view of a fragmentary portion of a car-truck equipped with the safety hanger of my invention in slightly modified form, and

Fig. 4 is a transverse section through a portion of the same, taken on the dotted line 4—4 of Fig. 3 and being on a larger scale than Fig. 3.

In Figs. 1 and 2 I illustrate my safety hanger as applied to a car truck having a spring plank 10, carrier suspension bars 16, 17 and safety guard bar members 19, 20 of the type shown and described in my pending application for Letters Patent Serial No. 717,693, filed June 4, 1924. The outer ends of the carrier bars 16, 17 are detachably secured to the outer ends of the safety guard members 19, 20 by hinge connections 11, and the inner end portions of said bars 16, 17 are supported within the channels of brackets 21 riveted to the spring plank. When the hinge connections 11 are freed, the bars 16, 17 may be pulled endwise from the brackets 21, and said bars may be restored to position by being pushed endwise into said brackets 21. The truss-rods 12 of the brake beams ride on the carrier bars 16, 17, as usual. The brake-beams have the compression members 13, struts 14, live lever 15, dead lever 22, dead lever guide, or brake-lever stop, 23, and bottom connection rod 24 connected at one end with the lever 15 by a pin 25 and at its other end with the lever 22 by a pin 26. Various types of carrier bars 16, 17 are well known, many being flat upwardly inclined bars, and hence I do not confine this invention to carrier bars having a convex upper surface.

The hanger of my invention is numbered, as a whole, 27, and said hanger is preferably

formed from a single metal rod of about five eighths of an inch in diameter. The hanger 27 is formed at its ends with eyes or loops 28, 29, respectively; and at about its middle portion said hanger is formed with an open-top depending yoke or saddle 30, through which the connection rod 24 freely passes. The hanger 27 extends diagonally below the spring plank from one carrier bar 16 to the diagonally opposite carrier bar 17, the inner end portion of the bar 16 being slipped through the eye 28 on the application of said bar to position and the inner end portion of the bar 17 being passed through the eye 29 when said bar is being applied to position. The eyes 28, 29 are bent to lie transversely of the truck and parallel with the sides of the spring plank 10, as shown in Fig. 1, and said eye 28 engages one side of the spring plank 10 where the eye encompasses the carrier bar 16, while the eye 29 engages a diagonally opposite portion of the other side of the spring plank where said eye 29 encompasses the carrier bar 17. The hanger 27 by the means described becomes very securely held and supported without the use of bolts or rivets; and the yoke or saddle 30 of the hanger is located below the spring plank. The eyes 28, 29 closely engage the bars 16, 17 and the adjacent portions of the spring plank and I propose that there shall be no looseness in the hanger when the same is in position. Should the hanger not tightly engage the parts supporting it, the hanger may be bent or forced downwardly at the yoke or saddle 30 to take up any slack that may exist in any part of the hanger. The hanger when in use is rigid and noiseless. In Figs. 1 and 2 I have shown the safety hanger 27 as applied to the diagonally opposite carrier bars 16, 17. The bars 16, 17 perform the two-fold duty of preventing the brake-beams, in case of accident, from falling to the track and of guiding or directing the beams to carry the brake-shoes properly against the wheels. Many car trucks do not possess the carrier bars 16, 17, but are provided with angle iron safety bars 31 to receive the brake-beams in the event of accident, whereby the beams are prevented from falling to the track. My safety hanger is applicable to the angle iron bars 31 as I illustrate in Figs. 3 and 4, in which 32 may designate the spring plank and 33 the safety hanger of my invention, this hanger being identical with the hanger 27 hereinbefore specifically described, except that its end-eyes or end-loops 34, 35 will be shaped to engage the angle iron bars 31, said bars being slipped through said eyes or loops or the eyes or loops being slid upon said bars.

In every instance my safety hanger extends from one side of the truck to the other below the bottom connection rod of the

brake mechanism and is applied to position without the use of bolts or rivets. The safety hanger is formed of one integral rod and will be manufactured with the end eyes or loops and intermediate yoke or saddle at the factory for assembly with the other parts of the truck wherever the same are to be installed.

I have illustrated the safety hanger as formed from a rod which is round in cross section but I do not, of course, confine the invention to the use of a round rod or to a rod of any particular shape in cross section.

What I claim as my invention and desire to secure by Letters Patent, is:

1. In a car truck having a spring plank and longitudinal bars at opposite sides of the truck extending below the brake-beams, a safety hanger for the bottom connection rod of the brake rigging comprising a rod having an open-top yoke or saddle for said connection rod and eyes or loops on its ends to transversely engage said opposite longitudinal bars at points close to the spring plank.

2. In a car truck having a spring plank and longitudinal bars at opposite sides of the truck extending below the brake-beams, a safety hanger for the bottom connection rod of the brake-rigging comprising a rod having an open-top yoke or saddle for said connection rod and eyes or loops on its ends initially shaped to closely transversely embrace said opposite longitudinal bars, said eyes or loops being formed to the shape of the bars and to allow said bars to be slipped into them on the assembly of the parts of the truck.

3. In a car truck having a spring plank and longitudinal bars at opposite sides of the truck, a safety hanger for the bottom connection rod of the brake-rigging comprising a rod having an open-top yoke or saddle for said connection rod and extending diagonally across the truck below the spring plank from one of said bars at one side of the spring plank to the other of said bars at the other side of the spring plank, the ends of said hanger rod being secured on said bars and said yoke or saddle being below the spring plank.

4. In a car truck having a spring plank and longitudinal bars at opposite sides of the truck, a safety hanger for the bottom connection rod of the brake-rigging comprising a rod having an open-top yoke or saddle for said connection rod and extending diagonally across the truck below the spring plank from one of said bars at one side of the spring plank to the other of said bars at the other side of the spring plank, the ends of said hanger rod having eyes closely receiving said bars and said yoke or saddle being below the spring plank.

5. In a car truck having a spring plank and longitudinal bars at opposite sides of the truck, a safety hanger for the bottom connection rod of the brake-rigging comprising a rod having an open-top yoke or saddle for said connection rod and extending diagonally across the truck below the spring plank from one of said bars at one side of the spring plank to the other of said bars at the other side of the spring plank, the ends of said hanger rod having eyes closely receiving said bars and said yoke or saddle being below the spring plank. 35

6. In a car truck having a spring plank and longitudinal carrier suspension bars for the brake-beams at opposite sides of the truck, a safety hanger for the bottom connection rod of the brake-rigging comprising a rod having an open-top yoke or saddle for said connection rod and extending diagonally across the truck below the spring plank from one of said bars at one side of the spring plank to the other of said bars at the other side of the spring plank, the ends of said hanger rod having eyes which lie parallel with the sides of the spring plank and receive said bars and said yoke or saddle being below said plank. 7. In a car truck having a spring plank and longitudinal carrier suspension bars for the brake-beams at opposite sides of the truck, a safety hanger for the bottom connection rod of the brake-rigging comprising a rod having an open-top yoke or saddle for said connection rod and extending diagonally across the truck below the spring plank from one of said bars at one side of the spring plank to the other of said bars at the other side of the spring plank, the ends of said hanger rod having eyes which lie parallel with the sides of the spring plank and receive said bars and said yoke or saddle being below said plank. 7. In a car truck having a spring plank and longitudinal carrier suspension bars for the brake-beams at opposite sides of the truck, a safety hanger for the bottom connection rod of the brake-rigging comprising a rod having an open-top yoke or saddle for said connection rod and extending diagonally across the truck below the spring plank from one of said bars at one side of the spring plank to the other of said bars at the other side of the spring plank, the ends of said hanger rod having eyes which lie parallel with the sides of the spring plank and receive said bars and said yoke or saddle being below said plank.

Signed at New York city, in the county of New York and State of New York, this 3rd day of July, A. D. 1924.

SETH A. CRONE.
